(57) **CLAIM**

The ornamental design for a display screen or portion thereof with print icon, as shown and described.

DESCRIPTION

FIG. 1 is a front view of a display screen or portion thereof with print icon showing the new design; and,

FIG. 2 is another front view of the display screen or portion thereof with print icon of FIG. 1, with some of the broken line subject matter shown in FIG. 1 removed, for the purpose of clearly illustrating the claimed subject matter; and,

FIG. 3 is a front view of the display screen or portion thereof with print icon of FIG. 1, shown with additional broken line subject matter; and,

FIG. 4 is a front view of the display screen or portion thereof with print icon of FIG. 2, shown with additional broken lines subject matter.

The outermost dashed broken lines in FIGS. 3 and 4 depict a display screen or portion thereof that form no part of the claimed design. The remaining broken lines illustrate portions of a graphical user interface and the icon that form no part of the claimed design.
